UNITED STATES PATENT OFFICE.

NATHAN BEMAN, OF SEATTLE, WASHINGTON.

BALLOT-POUCH.

No. 806,050.

Specification of Letters Patent.

Patented Nov. 28, 1905.

Application filed July 7, 1905. Serial No. 268,745.

To all whom it may concern:

Be it known that I, NATHAN BEMAN, a citizen of the United States, residing at Seattle, in the county of King and State of Washington, have invented certain new and useful Improvements in Ballot-Pouches, of which the following is a specification, reference being had therein to the accompanying drawings.

This invention relates to ballot-receptacles; and the object of the invention is the provision of a flexible device of this nature which is capable of being conveniently packed and transported either by manual labor or on horseback and is especially intended for use in mountainous districts where the roads are impassable for wheeled vehicles and where the various deposited ballots are required to be conveyed to the county-seats for recounting.

A further object of the invention is the provision of means for safeguarding the ballots within the pouch from all danger of being tampered with by irresponsible parties without their having to mutilate the receptacle.

The invention consists in the novel construction, arrangement, and adaptation of devices, as will be hereinafter described, and illustrated in the accompanying drawings, in which—

Figure 1 is a perspective view of a ballot-bag embodying my invention. Fig. 2 is an enlarged vertical section of a portion of the same. Fig. 3 is a cross-sectional view taken through 3 of Figs. 1 and 2 and looking upwardly.

The reference-letter A designates a sack or bag of a flexible material, such as leather or canvas, and is provided in proximity of its open upper end with a plurality of apertures a.

B is a disk cover, preferably of a stiff or rigid construction and desirably formed of metal and adjacent of its periphery is provided with an upwardly-extending groove C, which may advantageously be formed by stamping or flanging the cover first upwardly by a bend C' and thence downwardly by a reverse bend, thus forming folds b and b' and between which is inserted the upper marginal edge of the sack. The said cover-folds are each provided with oppositely-disposed apertures d and d', which are arranged to register with the perforations of the sack when the

edge of the latter is inserted between the said folds. E is a strap or the like, which is laced or passed in and out through the successive said holes of the sack and cover and having adjacent of one of its ends a staple e, adapted to be passed through and protrude outside of a slot e', provided in the other end when the strap is in its engaged position, and the ends are caused to overlap, as plainly shown in the drawings. After being thus connected the strap may be fastened by a seal or padlock F, connected to said staple, to reliably secure the cover in place. The said cover is provided with a ballot-receiving slot G and beneath which is a flap H, hinged to the cover by a rod I passing respectively through sockets g' and h of the cover and flap.

A spring J is coiled about the rod I intermediate the hinge connections h and has its ends extend outwardly in opposite directions to resiliently press the flap to close the said ballot-slot yet permit the depositing of the ballots from the outside as voted.

K is a staple connected or formed in the cover and extends downwardly through an aperture K in the flap H, whereby the flap can be secured by a padlock, by wiring, or by other suitable means after the local inspectors or judges have counted the ballots and returned them to the sack prior to the replacement of the cover.

For convenience in securing the sack to a horse an eyelet M may be formed or provided at the lower end of the sack.

The invention is of simple and inexpensive construction and is extremely useful in situations such as before alluded to.

Having described my invention, what I claim as new, and desire to secure by Letters Patent, is—

1. A device of the class described, comprising a flexible sack provided with a series of apertures positioned in proximity of its open end, a cover for said open end of the sack, said cover being provided with a ballot-inserting slot and a series of apertures corresponding to the apertures of the said sack, a strap adapted to be laced in and out through the respective said apertures of the sack and cover for detachably securing these parts together, and means for securing said strap in its engaged laced position, substantially as described.

2. In a device of the class described, the combination with the sack having a number of lacing-apertures in proximity of its open end, of a slotted cover adapted to close said end
5 and provided with a flange having therein a series of apertures corresponding with the apertures of the said sack, a lacing-strap, an openable closure for the slot of said cover,

and detachable means to prevent the opening of the said closure, substantially as described. 10

In testimony whereof I affix my signature in presence of two witnesses.

NATHAN BEMAN.
